UNITED STATES PATENT OFFICE.

ADOLPH LISSNER, OF NEW YORK, N. Y.

FUR-CUTTING GUIDE.

SPECIFICATION forming part of Letters Patent No. 269,867, dated January 2, 1883.

Application filed November 6, 1882. (No model.)

To all whom it may concern:

Be it known that I, ADOLPH LISSNER, a citizen of the United States, residing in the city, county, and State of New York, have invented 5 a new and useful Fur-Cutting Guide, of which the following is a specification, which will enable others skilled in the art to which it appertains to make and use the same.

My invention relates to improvements in 10 fur-cutting guides which are intended to cut strips of fur for use as trimmings; and the objects of my invention are, first, to provide a firm ruler or guide for the knife without previously marking the fur, as well for narrow 15 strips as for wide strips; second, to provide a means by which the rulers or guides, after being used, can all be simultaneously restored to their normal positions, ready for use again. I attain these objects by the mechanism illustrated in the accompanying drawings, in 20 which—

Figure 1 is a top view of the apparatus with the guides in their normal positions, ready for use. Fig. 2 is a part of the same, with the 25 guides turned over on their other sides after having been used. Fig. 3 is a vertical section of the apparatus with the guides in their normal positions and the levers underneath in their normal positions. Fig. 4 is a vertical section, showing in detail the operation of the 30 guides and levers of the apparatus; and Fig. 5 is a vertical section of the slide and clamp employed to keep the apparatus in place.

Similar letters refer to similar parts throughout the several views.

A is a square frame, made of tin or other thin metal strengthened on its outer sides by wire encircled by the outer edges of the frame. This frame is made of any desired size, and 40 the inside space is also a matter of convenience.

B is one of a number of guides covering the entire top of the frame A at even distances. These guides are made of the same material as that of the frame. The guide B is secured to 45 the frame A by a hinge, a, fastened to the guide and frame at the upper and lower sides, so that the guide is left free to turn and lie either with the upper face of the guide flat on the frame A, as shown in Fig. 1, or with the lower face

of the guide flat on the frame, as shown in Fig. 50 2. The guide B is strengthened by turning a part of its edges b and c on itself.

b is the edge of the guide against which the knife is drawn in cutting. When the guides are in position for use the edge b rests on the 55 pelt of the fur underneath and serves to hold the fur in place while cutting.

g is one of a number of flat-headed wires secured to the under and lower side of the frame A, and parallel with its face. These 60 wires are placed, at even distances, directly underneath the hinges a, and extend into the space within the frame A. Upon this extension of the wire g is pivoted a lever, d, so that it may move freely and perpendicularly 65 between the inner edge of the frame A and the head of the wire g. This lever is made of the same thin material as that of the frame, and is in the form of a contracted cone, and is normally placed with its shortest side on a line with the 70 face of the frame A.

e is a flat bar, to which are secured similar flat-headed wires, g', and at like distances to the wires, g. The lever d is likewise pivoted at the extreme end of the longest arm to the 75 wire g', so that when the bar e is moved laterally to one side, the free lever-arm will rise above the face of the frame A and raise the used guides B, lying upon it, to a perpendicular position, as shown by dotted line 2 in 80 Fig. 4. The bar e is provided with a handle, h, to facilitate the grasp, and a contractile spring, S, secured to the bar, and a projection, f, which has the tendency to draw the bar e toward it, and so keep the lifting-edges of the levers d 85 down on a level with the face of the frame A.

E is one-half of a hinge, and is adapted to fit into the depression made for it in the clamp C. The other half of the hinge E is secured to the under side of the frame A, so as to allow the unsecured arm of the hinge free play up and down. The clamp C is adapted to be secured to a cutting-board by screws, and is provided with a head-screw, D, to secure the hinge. These apparatuses come in sets of 90 eight or more, with guides B of different widths. The clamp C is fastened to the cutting-board, so that the frame A, when fastened in the

clamp C, will extend below the board a sufficient distance to give free play to the levers d and bar e.

To operate this apparatus I take the one with the width of guide required, slide the hinge E into the depression in the clamp C, turn the head-screw D and secure the apparatus firmly to the board, lift the frame on its hinge E, place underneath the fur to be cut, pelt upward, and then shut down the frame. Then I arrange the guides B as in Fig. 1 by pulling the handle h. I next take a fur-cutting knife, grasp the uncut edge of the fur with my left hand, and run the knife through the entire length of the fur, steadyng the knife against the edge b of the guide, and throw the strip of fur so cut aside. Then I raise the guide so used and turn it over on its other side and out of the way of a new strip to be cut, and proceed as before, continuing the operation until the fur is exhausted. I then replace the guides by pulling the handle h, which brings all the guides into a perpendicular position, and then, by running a finger across them,

lay them all on their right sides, ready for use again.

Having fully described my invention, what I desire to claim and secure by Letters Patent is—

1. In a fur-cutting guide, the combination of the frame A with the hinged guide B and its turned edges b and e, substantially as set forth.

2. The combination, in a fur-cutting guide, of the movable guides B with the levers d, wires g and g', and bar e, substantially as described, for the purposes specified.

3. The combination, in a fur-cutting guide, of the frame A with the hinge E and clamp C and D, substantially as described.

4. In a fur-cutting guide, the combination of the frame A, guides B, hinges a, turned edges b and e, bar e, wires g and g', levers d, and spring S, substantially as described, and for the purposes specified.

ADOLPH LISSNER.
